UNITED STATES PATENT OFFICE.

WILLIAM G. SCHMIDLIN AND JEREMIAH W. DRISCOLL, OF NEW YORK, N. Y.

IMPROVEMENT IN STREET-LAMPS.

Specification forming part of Letters Patent No. 123,516, dated February 6, 1872.

To all whom it may concern:

Be it known that we, WILLIAM G. SCHMIDLIN and JEREMIAH W. DRISCOLL, of the city and State of New York, have invented an Improvement in Street-Lamps; and the following is declared to be a correct description of the same.

Street-lamps have been made of metallic frames, usually square, and resembling two truncated pyramids united at their bases. Hexagonal lamp-frames have also been made in this general shape; but, in all instances, the lamp-frames take a very large space when packed for transportation in consequence of being permanently connected throughout the entire frame.

Our invention relates to an improved means for connecting the two conical portions of the lamp-frame so that they can be disconnected for transportation and packed into a small compass, either with or without the glasses being in place. We also apply a reservoir for oil or other liquid hydrocarbon in such a manner that the same is permanently connected with the other portion of the lamp instead of being separate and requiring careful connection after the lamp reaches its destination, as heretofore usual.

In the drawing, Figure 1 is a vertical section diagonally and through the corner-frames of a square lamp, and Fig. 2 is a section of the top band of the body of the lamp and the bottom band of the conical top.

The lamp is made of the two principal parts, the body and the removable conical top. The body of the lamp is made with the bottom frame *a* and corner-frame pieces *b*, as usual, and a door, not shown in the drawing, is applied in the known manner. The top band *d*, instead of being made as a projecting water-table, as usual, is inclined inwardly, as at 2, in order that the lower band *e* of the conical frame *f* may come outside of the same and shed the water outwardly instead of its running into the lamp. The band *e* also renders the frame of the removable conical top sufficiently strong, and upon this band *e* are the hooks *i* that are bent up to hold the glass *h* in place. The hooks *k* upon the band *d* are, as usual, for holding the lower glasses *l*. At the top of the removable

frame *e f* is the chimney or cap *m*, that should be removable, as usual. It will now be understood that the conical top and bottom portions of a number of lamps can be nested together and packed into a small compass, or the top part inverted into the bottom in a single lamp for transportation; and, when put together and secured, the lamp will be as reliable and available as those that are made of a frame that cannot be separated. To connect these parts we make use of vertical wires on one part, entering short tubes or loops on the other. The wires *o o* are shown as passing into the short tubes *r r* upon the body of the lamp; and at *s* is a wire upon the body of the lamp to pass up into a loop or short tube upon the removable top portion of the lamp, and this wire should be made with a screw-thread to receive a nut; or any other fastening may be employed. The reservoir *t* is made as a tube, running around outside the top band of the body of the lamp, and secured thereto permanently; and the tube *u* passes down from this reservoir and in through the frame, and terminating with a burner in the center of the lamp.

By this construction the reservoir is permanently connected in its place, and risk of injury and leakage prevented.

The conical bottoms, sometimes applied at the lower part of the lantern body, may also be removable and secured by wires the same as the upper portion.

We claim as our invention—

1. The band *d* sloping inwardly at its upper edge 2, in combination with the removable top frame of the lamp, with the lower band *e* coming outside of this band *d*, as and for the purposes set forth.

2. The removable upper frame of the lantern in combination with the connecting-wires *o o* and loops or tubes *r* to secure the same to the lower part of the lamp, as set forth.

Signed by us this 1st day of December, A. D. 1871.

WM. G. SCHMIDLIN.

JEREMIAH W. DRISCOLL.
